UNITED STATES PATENT OFFICE.

CHARLES W. HUBBARD, OF WESTON, MASSACHUSETTS.

PROCESS OF AND APPARATUS FOR HANDLING YARN.

1,209,968.

Specification of Letters Patent.

Patented Dec. 26, 1916.

Application filed December 4, 1913. Serial No. 804,754.

To all whom it may concern:

Be it known that I, CHARLES W. HUBBARD, a citizen of the United States, residing at Weston, county of Middlesex, State of Massachusetts, have invented an Improvement in Processes of and Apparatus for Handling Yarn, of which the following description, in connection with the accompanying drawing, is a specification, like characters on the drawing representing like parts.

This invention relates to process of and apparatus for handling yarn preparatory to its being woven into cloth or made into twine.

15 In the textile industry it is now the common practice to subject the yarn to a plurality of operations preparatory to weaving it into cloth, or making it into twine, such, for instance, as spinning, twisting, spooling, 20 doubling, winding and balling, and these operations are carried on on different machines so that the carrying out of these various operations necessitates the repeated transfer of the yarn mass from one machine 25 to another. The operation of removing the yarn mass from one machine is commonly termed "doffing," while the operation of placing the yarn mass in the next machine for the next operation is commonly termed 30 "creeling." The repeated creeling and doffing which are necessary in transferring the yarn from one machine to another consume a considerable time and also involve a large amount of labor, all of which is an important 35 factor in the final expense of producing the yarn.

It is the object of my invention to provide a novel process of and apparatus for handling yarn by which the time and expense incident to the operations of doffing and creeling as now carried on are very largely eliminated, thus enabling me to produce a 40 yarn at a greatly decreased cost from that now in vogue.

45 In carrying out my invention I provide means whereby the two successive operations are performed simultaneously in one machine, the construction being such that the yarn is delivered from each operation directly into the yarn receiver from which it is drawn for the next succeeding operation, thus obviating any hand labor in effecting a transfer of the yarn mass from one machine or mechanism to another. With 50 this arrangement it is possible to pass the yarn from one operation to the other con-

tinuously without the usual doffing and creeling processes, these being automatically taken care of in the treatment of the yarn.

I find that my invention is particularly advantageous when used in connection with winding and twisting apparatus, such as shown in my Patents No. 795,981 and No. 795,982, both dated August 1, 1905, and in my co-pending application Se. No. 804,753, filed December 4, 1913, and therefore I have elected to illustrate my invention herein as it would be used in connection with apparatus of this general type. I desire to state, however, that the invention is not limited 70 in its use to spinning and twisting apparatus of the general type referred to in my said patents and application.

In the accompanying drawings I have shown some selected embodiments of the invention from which the principle thereof will be readily understood, and Figures 1 to 5 inclusive are diagrammatic views illustrating different ways of carrying out my methods; Fig. 6 is a vertical sectional view 75 through an apparatus which includes a winding and twisting device of the type shown in said co-pending application; Fig. 7 is a front view of an apparatus such as shown in Fig. 1; Fig. 8 is a detail showing 80 the head used during the doffing of the yarn.

Before entering into a description of my present invention I will first refer briefly to the yarn receiver with its means for 90 twisting and winding the yarn therein which I have herein illustrated and which is set forth more at length in my said co-pending application. This yarn receiver comprises a rotary yarn holder 1, mounted 95 on a vertical shaft 2 by which it is rotated, and which has therein a yarn support 3 on which the yarn mass 4 is built up. Situated within the yarn holder 1 is a spindle 5 which extends down through the shaft 2 and is 100 adapted to receive either a winding head 7, as seen in Fig. 6 that is constructed to lay the yarn on the yarn support in transverse layers, or a pressure head 8, as seen in Fig. 8, which is used when the yarn is 105 being doffed or withdrawn from the yarn receiver. The spindle 5 and shaft 2 carrying the yarn holder are rotated at different relative speeds by means of gears 9 and 10 which mesh with gears 11 and 12 110 on the shaft 2 and spindle 5, respectively, said gears 11 and 12 being of the same size

and having the same number of teeth. The two gears 9 and 10 are rigid with each other and are driven from a shaft 13 by any suitable means, such as bevel gears 14. Said gears 9 and 10 are of the same size, but one gear has a greater number of teeth thereon than the other, and as a result the shaft 2 and spindle 5 will be rotated at different speeds. The teeth of the gears 9, 11, 10 and 12 are so shaped as to permit the gears to freely mesh and rotate without binding. The winding head 7 is provided with an oscillating thread guide 15 and is provided with suitable differential mechanism constructed so that as the yarn holder and shaft 2 are rotated at their different speeds the yarn mass will be built up in transverse layers. The upper end of the spindle is shown as journaled in a head 18 which is detachably secured to the top of the holder 1, and this head is provided with a trunnion 19 which is rotatably and slidably mounted in a suitable cap plate or bearing 20, the construction being such that the head 18 can be removed from the yarn holder, thus permitting the spindle 5 and the winding head 7 or the pressure plate 8 to be withdrawn or replaced in position as desired. When the yarn is being doffed from a yarn receiver the winding head 7 and spindle 5 are removed (the spindle being detachably connected to its driving gear) and the pressure plate 8 is placed on the yarn mass as seen in Fig. 8. This pressure plate merely serves to hold the yarn in place as it is withdrawn, the yarn passing up through a hole 41 in the pressure plate and through the bore in the head 18, as seen in Fig. 8. Inasmuch as my present invention does not relate to this particular construction of yarn receiver and the latter is fully described and illustrated in my said co-pending application, I do not deem it necessary to further illustrate it herein.

When my present invention is carried out in connection with a yarn receiver of this type, I propose to use such a yarn receiver for receiving the yarn after the spinning or twisting operation and then to use the same yarn receiver as the creel for the subsequent winding, spooling or doubling operations, and I also propose to provide a machine so constructed that the successive operations of winding, spooling, doubling, etc., can be carried out thereon simultaneously. With my invention two or more successive operations are performed in the same machine and the yarn is delivered from each operation directly into the yarn receiver from which it is drawn for the next succeeding operation, so that no manual labor is required in removing or doffing the yarn from one machine at the end of one operation and placing the yarn in another machine (which operation is usually referred to as creeling)

for the next succeeding operation. The step, therefore, of delivering the yarn into a yarn receiver for one operation constitutes the step of supplying yarn to a yarn receiver for the next succeeding operation, and since both operations are carried out in the same machine a saving in labor is thereby effected.

In Fig. 1 I have shown diagrammatically how my invention would be applied to the doubling, twisting and spooling or winding processes which consist in taking a plurality of strands from different sources of supply and twisting or doubling them together and winding them onto a yarn receiver and then transferring the twisted or doubled strand from the yarn receiver onto a spool or reel. As heretofore practised, this operation of doubling and winding has necessitated the use of two different machines, in one of which the various strands are doubled or twisted together, and then wound onto a bobbin, and in the other of which the yarn is wound from the bobbin onto the reel or spool. The use of such two machines has, of course, necessitated the transfer of the yarn from one to the other.

In applying my invention to this process of doubling, twisting and spooling, I propose to provide a machine which includes a plurality of yarn receivers 21, each preferably of the type shown in Figs. 6, 7 and 8, each yarn receiver having therein a yarn mass which furnishes one of the strands 22 of the doubled strand. Each of these yarn receivers will be provided with a presser plate 8, as shown in Fig. 8, which simply rests on the yarn mass and holds it in place as it is withdrawn through the head 18 at the upper end of the holder 1. The strands 22 of yarn from the various yarn receivers are fed to a twisting and winding device 23 which may be similar to that shown in Fig. 6 and which comprises a yarn holder with its yarn support and a winding head within the yarn holder adapted to twist the yarn delivered thereto and to build up a yarn mass in the yarn holder. As the yarn mass is delivered to the yarn receiver or winding apparatus 23 the various strands 22 are twisted together, as will be obvious. The device also comprises another yarn receiver 24 similar to the yarn receiver 23 except that instead of having the winding head 7 therein it is provided with a presser plate 8. The yarn is taken from this yarn receiver 24 and delivered to the spool or reel 25. In the operation of the mechanism illustrated diagrammatically in Fig. 1, the strands 22 of yarn will be taken from the yarn receivers 21, twisted together, and delivered to the yarn receiver 23, while the twisted and doubled strand in the yarn receiver 24 is transferred to the reel 25. When the yarn receiver 23 is filled and the yarn receivers 21 and 24 are empty, then fresh filled yarn

receivers 21 are substituted for those which have been emptied and the winding head 7 in the yarn receiver 23 will be exchanged for the presser plate 8 in the yarn receiver 24, and the strands of yarn from the filled yarn receivers 21 will be fed into the empty yarn receiver 24 and wound therein, while the doubled strand in the filled yarn receiver 23 will be fed to the reel 25, as shown by dotted lines in Fig. 1. With this arrangement the yarn receivers 23 and 24 are interchangeably used and the filling of the yarn receiver 23 is carried on simultaneously with the emptying of the yarn receiver 24 and vice versa.

In carrying out the above operations I propose to so drive the yarn receiver 23 that it will put into the doubled strand about one-half the required amount of twist and then when said strand is taken from said yarn receiver to be wound onto the reel 25, the yarn receiver is rotated as the doubled strand is withdrawn therefrom, thereby putting into the strand the other half of the desired twist between the yarn receiver and the reel. The advantage of this is that the doubled yarn can be delivered into the yarn receiver 23 at a much greater speed than if it were necessary to put the entire twist into the doubled strand between the yarn receivers 21 and 23 or 24. With this arrangement the yarn receivers 23 and 24 act alternately as the creels for the reel 25, and the doffing and creeling operations are carried on automatically and continuously and without the necessity of any labor.

In Figs. 2 and 3 I have shown an arrangement by which the operations of spinning, and spooling can be carried out continuously in a single machine. These figures are diagrammatic entirely and are not intended to show details of construction. The machines shown in said figures comprise a frame of any suitable length which is made up in sections, each alternate section comprising a plurality of spools or reels 26 and the other sections each having a plurality of pairs of spinning or drawing rolls 27. These sections are shown as alternately arranged and each section has six spools and six pairs of drawing rolls, although the number is not essential. Associated with the frame thus constituted is a plurality of sets of yarn receivers of the type above referred to. These yarn receivers are conveniently mounted on a frame 28, and this frame and the part of the machine carrying the reels 26 and drawing rolls 27 are movable relative to each other, so that they can be shifted relative to each other in a direction longitudinally of the machine. This may be accomplished by making either part movable. In the drawings the frame carrying the rolls 27 and reels 26 is movably mounted on the frame 28. The yarn receivers are arranged in sets, there being one

set for each section of the machine, and in the illustrated embodiment of the invention there are six yarn receivers in each set. The alternate sets of yarn receivers are designated 29 and the other sets by 30. As shown in Fig. 2, the yarn receivers 30 are receiving yarn from the drawing rolls 27, each yarn receiver operating to twist and wind up therein an end delivered from one of the pairs of drawing rolls. The yarn receivers 29 which have been previously filled are delivering their yarn to the spools 26.

In the operation of the machine the yarn receivers 30 are being filled simultaneously with the emptying of the yarn receivers 29, and when the yarn receivers 30 are filled and the yarn receivers 29 are empty, then the carrier 28 and the spools and drawing rolls are shifted longitudinally relative to each other into the position shown in Fig. 3 thereby to bring the filled yarn receivers 30 opposite the spools 26 and the empty yarn receivers 29 opposite the drawing rolls 27. The machine will be built with one extra set of spools or reels 26, there being a set at each end of the machine, as shown in the drawings. This arrangement is adopted so that all of the yarn receivers may be utilized at all times. It will be understood, of course, that when the yarn in the receivers 29 has been transferred to the reels 26, said reels will be removed and empty reels will be substituted in their place. With this construction the emptying of the yarn receivers which are filled from the drawing rolls is carried on continuously and automatically in the operation of winding the yarn on the spools 26 and simultaneously with the filling of the other yarn receivers, and the filling of said other yarn receivers is performed automatically and simultaneously with the spinning operation. There is no labor nor time spent in removing the yarn receivers from one machine and placing them in another machine for a different operation, the only labor necessary at the end of any run being to change the spools 26, to shift the relative position of the carrier 28 and spools and drawing rolls, and to exchange the winding heads 7 and spindle 5 in the yarn receivers 30 for the presser plates in the yarn receivers 29 and vice versa.

In Figs. 4 and 5 I have shown diagrammatically a machine adapted for spinning, twisting and doubling and winding, and arranged so that all of these operations are carried out simultaneously and without transferring the yarn from one machine to another. In these figures 27 indicate drawing or spinning rolls and 30 designate a set of yarn receivers adapted to receive the yarn from the drawing rolls. 29 designate another set of yarn receivers similar to the yarn receivers 30, and 31 and 32 designate other yarn receivers larger than the yarn re-

receivers 29 and 30 and adapted to receive doubled yarn from the latter receivers. 33 designate spools or reels on which the yarn is finally wound. All of these parts can be 5 conveniently mounted on a single frame and form part of the same machine.

In the operation of the machine the yarn receivers 29 are supposed to have been previously filled with spun yarn while the yarn receivers 30 are empty. The yarn receivers 32 have been filled with doubled yarn while the yarn receivers 31 are empty. The roving or ends from the drawing rolls 27 are fed into the yarn receivers 30, the yarn being 15 spun and twisted and wound up in said yarn receivers. The ends from the filled yarn receivers 29 are fed to the yarn receivers 31, each yarn receiver 31 having a doubled end delivered thereto. The filled yarn receivers 20 32 are delivering their doubled ends to the reels 33.

The operation of the machine will be so timed that the yarn receivers 30 and 31 will be filled at approximately the same time as 25 the yarn receivers 29 and 32 are emptied, and when this condition exists the drawing rolls 27 are shifted laterally into position to deliver yarn to the yarn receivers 29, the winding heads 7 in the yarn receivers 30 and 30 31 are exchanged for the presser plates in the yarn receivers 29, 32, the ends from the filled yarn receivers 30 are fed into the empty yarn receivers 32, while the doubled ends from the yarn receivers 31 are fed to the 35 reels 33, all as shown in Fig. 5. The operation is then continued until the yarn receivers 29 and 32 are filled and the yarn receivers 31 and 30 are empty, at which time the change is made back to the arrangement 40 shown in Fig. 4.

In all of the above operations I propose to place approximately one-half the twist in the yarn while it is being delivered to and laid in one of the yarn receivers and then 45 to rotate the yarn receiver as the yarn is taken out therefrom for the second operation, thereby to put into the yarn the rest of the desired twist. For instance, in Figs. 2 and 3 about one-half the twist desired will 50 be put into the yarn between the drawing rolls 27 and the yarn receivers 29 or 30, and then the other half of the twist will be put into the yarn between said yarn receivers and the spools 26. This can be readily ac- 55 complished by merely rotating the yarn receivers as the yarn is being doffed therefrom, the rotating of the yarn receivers giving the additional twist to the yarn. Similarly in Figs. 4 and 5 approximately half the twist 60 may be put into the yarn as it is delivered to the yarn receivers 31 or 32 and the other half of the twist put into the yarn as it is delivered from the yarn receivers to the reels 33. As stated above the advantage of this is 65 that the yarn can be twisted much more rap-

idly than when all the twist is put into it in the first instance, for the fact that only about half the desired twist is put into the yarn during the first operation enables the yarn to be run off from the drawing rolls at a 70 greatly increased speed and the placing of the additional twist in the yarn as it is delivered from the yarn receivers of the reel 26 does not affect the speed at which the yarn can be handled. Therefore, by putting 75 in the desired twist in two successive operations the output of yarn can be nearly doubled.

It will be further noted that in all of the embodiments of the invention shown, the 80 step of supplying the yarn to one yarn receiver for one operation, (which may be termed the creeling operation) constitutes the step of delivering the yarn from the next preceding operation (which may be referred to as doffing the yarn). There is, therefore, no separate doffing of the yarn from one operation and transferring the yarn to another machine or creeling the yarn for the next succeeding operation. The only 85 exception to this is that there must be an initial creeling by hand at the beginning of all the operations and the final doffing from the spools 26 must be done by hand, but all the intermediate doffing and creeling operations are performed without removing the 90 yarn receiver from the machine.

While I have illustrated herein some selected embodiments of my invention I do not wish to be limited to the constructional 100 details shown.

Having fully described my invention, what I claim as new and desire to secure by Letters Patent is:—

1. In a device of the class described, the 105 combination with a plurality of sets of drawing rolls, of a plurality of sets of drums or spools, said sets of drawing rolls and sets of drums or spools being alternately arranged, a plurality of sets of yarn receivers, 110 and means to shift the relative position of the yarn receivers and the drawing rolls and spools, the alternate sets of yarn receivers being situated in one relative position to receive yarn from the drawing rolls, and the 115 other sets of yarn receivers being situated to deliver yarn to the spools or drums, and in another relative position the first-named sets of yarn receivers being adapted to deliver yarn to the spools or drums, and the other 120 yarn receivers being adapted to receive yarn from the drawing rolls.

2. In a device of the class described, the 125 combination with two sets of yarn receivers, drawing rolls coöperating with the yarn receivers of one set, spools coöperating with the yarn receivers of the other set, means asso- 130 ciated with each of the yarn receivers of the first-named set to twist the yarn delivered thereto and to built up a yarn mass

therein, the yarn from the yarn receivers of the other set being delivered to the spools and wound thereon, said yarn receivers and the spinning rolls being movable relative to each other whereby when the yarn receivers of one set are filled and those of the other empty the spinning rolls and yarn receivers may be moved relative to each other to bring the empty yarn receivers into coördination

with the drawing rolls and the filled yarn receivers into coördination with the spools.

In testimony whereof, I have signed my name to this specification, in the presence of two subscribing witnesses.

CHARLES W. HUBBARD.
